D25-145

EX

D9075

OR D 5,562

UNITED STATES PATENT OFFICE.

JOSEPH WOOLMAN REEVES, OF PHILADELPHIA, PENNSYLVANIA, ASSIGNOR
TO WILLIAM H. FRENCH, OF SAME PLACE.

DESIGN FOR CENTER PIECE FOR CEILINGS.

Specification forming part of Design No. 5,562, dated February 27, 1872.

To all whom it may concern:

Be it known that I, JOSEPH WOOLMAN REEVES, of the city and county of Philadelphia, in the State of Pennsylvania, have invented and produced a new and original Design for a Center Piece for Ceilings; and I do hereby declare the following to be a specification thereof.

The nature of my design is shown in the accompanying engraving, which forms a part of this specification, and represents so much of a center piece, made according to the said design, as is necessary to show the said invention.

The leading features of this design are as follows: The incised work A within the lancet-figure B; the incised work C between said lancet-figures and the circular molding D; the incised work E between the circle F and oval G; and the incised border H between E and the said oval.

The details of the ornamentation may, of course, be varied at pleasure.

What I claim as my invention, and desire to secure by Letters Patent of the United States, is—

1. The incised work A within the lancet-figure B.
2. The incised work C between the lancet-figures B B and the circular molding D.
3. The incised work E between the circle F and oval G.
4. The incised border H between the incised work E and the oval G.
5. The entire design, substantially as shown.

JOSEPH WOOLMAN REEVES.
